UNITED STATES PATENT OFFICE.

FREDERICK E. GLAZE, OF DENVER, COLORADO, ASSIGNOR, BY MESNE ASSIGNMENTS,
TO THE SPANGLER MANUFACTURING COMPANY, A CORPORATION OF COLORADO.

SELF-CLEANING SPARK PLUG.

Application filed May 9, 1919, Serial No. 295,873. Renewed December 28, 1923.

To all whom it may concern:

Be it known that I, FREDERICK E. GLAZE, a citizen of the United States, residing at the city and county of Denver and State of Colorado, have invented certain new and useful Improvements in Self-Cleaning Spark Plugs; and I do declare the following to be a full, clear, and exact description of the invention, such as will enable others skilled in the art to which it appertains to make and use the same, reference being had to the accompanying drawings, and to the characters of reference marked thereon, which form a part of this specification.

The object of this invention is to provide a spark plug in which the electrodes are automatically cleaned and the body of the plug, particularly the porcelain insulator, is cooled and also kept clean. It is also an object of the invention to provide a plug by means of which priming may be easily accomplished, and whereby a saving will be made in gas consumption and an increase in power will be obtained.

Briefly, the invention comprises the ordinary shell and porcelain insulator, the electrode which passes through the porcelain being hollow. Within the electrode there is mounted a valve stem, on the inner end of which a valve is provided which seats within the electrode. The stem is shaped to permit the passage of air between it and the electrode when the valve is unseated. The valve is normally retained in its seat by means of a spring mounted on the outer end of the stem, whose tension preferably may be controlled by means of an adjustable device, such as a nut. By this construction the valve is unseated by suction in the engine and pure air is drawn in through the plug, whereby the lower chamber is cleared of foul or spent gases and the passage of air past the electrodes keeps them clean.

In the drawings:

Fig. 1 is an elevation of a plug equipped with my improvement.

Fig. 2 is a central longitudinal section therethrough.

Fig. 3 shows the hollow electrode.

Fig. 4 is a side view of the valve stem,

looking in the direction of the arrow 4 of Fig. 3.

The ordinary shell 10 is threaded at 12, whereby it may be screwed into the cylinder of an internal combustion engine. The end 55 of this shell is provided with a baffle plate, apertured at its center, as indicated at 14, and the shell is equipped with an electrode 15, overhanging the aperture. A hollow porcelain insulator 16 is fitted into the shell 10, as shown, seating on a copper-asbestos or other suitable gasket or gland 17. Opposite to the gland 17 a copper or other suitable gasket or gland 18 is positioned, against which the bushing 19 bears, which is threaded into the shell 10 to retain the insulator in position. Within the insulator, the hollow electrode is positioned, this comprising, as shown, two parts 20 and 21, threaded together, as indicated at 22. The inner portion 21 of the electrode passes through the cavity 23 of the insulator and into proximity with the electrode 15 for sparking purposes. The electrode portion 21 seats against a gasket 24, positioned on a corresponding shoulder in the insulator 16. A T-shaped air passage 25 is provided in the electrode portion 21, this passage communicating with a chamber 26 within the portion 20. The valve 27 is adapted to move in this chamber 26 and when in normal position to engage the seat 28; the valve stem 29 extends through a corresponding passage in the electrode to a point beyond the plug, and is flattened.

A brass washer 30, positioned above the electrode, bears upon the insulator 16 and upon this there rests a split spring 31. A lock nut 32 bears against the spring 31 and the washer 30, this nut having a terminal 90 attaching groove 33. Positioned upon the top of the nut 32 is an insulating washer of asbestos or other suitable material, which separates the nut 32 from a priming cup 35, the object of this washer being primarily to insulate the spring 36, which engages the cup 35, from the plug proper, in order to avoid destroying the temper of the spring. The tension of the spring 36 is controlled by some adjustable means, such as a nut 37, 100

mounted upon the threaded portion 38 of the stem 29 making possible the control of the amount of air admitted through the plug. In operation of the device, when strong suction is created in the engine on which the plug is used, the valve 27 will be withdrawn from its seat against the tension of the spring 36, whereby air will be drawn through the hollow electrode, past the valve 27, and into the chamber 23, thereby filling this chamber 23 with pure air and clearing it of foul or spent gases. This will prevent fouling of the porcelain and the adjacent parts. As the air is drawn through the aperture 14 in the baffle plate 13, the air current will clean the electrodes 21 and 15. As soon as suction is relieved within the engine, the spring 36 will restore the valve 27 to its seat and as a result no compression whatever will be lost in restoring the valve, as would be the case if no spring or similar means were used. When the engine is doing considerable work and the throttle is wide open, or nearly so, the suction in the cylinder will be relieved through the carburetor to such an extent that it will not be able to withdraw the valve from its seat against the tension of its spring 36 until the speed of the engine has picked up and again created an excess of suction. Therefore, in such cases, where it is desired to have a very rich mixture, there will be no possibility of diluting this mixture with air drawn through the plug at a time when it is undesirable. It will, therefore, be seen that air is admitted through the plug only when it is desirable.

When priming is necessary, a small quantity of priming fluid, such as ether or gasoline, will be poured into the priming cup 35. When the engine is started, the first suction stroke will draw this priming fluid down through the plug and past the electrodes 15 and 21, bringing it directly to the point where ignition takes place, the air following the charge during successive strokes, cleaning out the chamber 23.

I claim:

1. A spark plug having a chamber at its inner extremity, an electrode whose inner portion passes through said chamber, the electrode having a cavity intermediate its extremities, which cavity communicates with the atmosphere by a central longitudinal passage and with the upper portion of said chamber by ducts, a stem movable in the longitudinal passage of the electrode and having a valve adapted to seat in the upper portion of said cavity, and yieldable means for normally holding the valve in the seated position.

2. A spark plug having an electrode whose lower part is spaced from the adjacent portion of the insulating member, the said electrode having a chamber intermediate its extremities, said chamber being in commun-

cation with the atmosphere by a longitudinal passage and with the upper portion of said space by ducts, and a stem movable in said longitudinal passage of the electrode and having a valve normally seated in the upper portion of said electrode chamber.

3. A spark plug having an electrode provided with a chamber intermediate its extremities and ducts communicating with said chamber for the entrance and exit of gas, a stem movable in the inlet duct and having a valve located in said chamber and a spring acting on the stem to normally close the inlet duct.

4. A spark plug comprising a shell, a baffle on said shell and having an aperture therein, an electrode also on said shell and overhanging said aperture, a second electrode positioned in said aperture, a chamber within said shell and connecting with the aperture, said second electrode having a passage therethrough connecting said chamber with the atmosphere, a valve in said passage, a stem on said valve, and yieldable means connected with said stem to retain the valve in its seat normally, said yieldable means being adapted to be operated by the strong suction of an engine on which the plug is used when the engine is idling but inoperable by the weak suction produced in the engine when the throttle is first opened.

5. In a spark plug having electrodes arranged to provide a spark gap therebetween, a chamber within said plug, one electrode having a passage therethrough adapted to establish communication between the atmosphere and said chamber, this electrode being relatively stationary with the body of the plug when the parts are assembled, a seat in the passage through the electrode, a stem movable in said passage and having a valve member adapted to engage said seat, and yieldable means connected with said stem to normally retain said valve in said seat, said yieldable means being of such character as to permit the said valve to be opened automatically by the engine suction when the plug is in use, and adjustable means to adapt the plug to engines of varying suction, and located at the outer extremity of the plug where it is exposed for purposes of adjustment and removed from the heat of the engine.

6. A spark plug having electrodes arranged to provide a spark gap therebetween and having a chamber at its inner extremity in communication with said gap, one electrode being composed of two separable parts, one part having a longitudinal passage communicating with the atmosphere and provided with a seat, a stem movable in said passage and having a valve member adapted to engage said seat, the said passage being large enough to allow fluid to flow therethrough around the stem, yield-

able means connected with said stem to retain said valve normally in its seat, the two part electrode having a chamber between its two members and in which chamber the said valve is adapted to move, the last named electrode having ducts in communication with said electrode chamber whereby fluid entering the chamber is di-

rected to the outer surface of the electrode and finally enters the first named chamber, the yieldable means being adjustable and also of such character as to permit the valve to open automatically in response to the engine suction when the valve is in use. 10

In testimony whereof I affix my signature.

FREDERICK E. GLAZE.
